CLOTHES WASHING MACHINE

James B. Kirby, West Richfield, Ohio, assignor,
by means assignments, to The Apex Electrical
Manufacturing Company, Cleveland, Ohio, a
corporation of Ohio, as trustee

Application May 10, 1929, Serial No. 362,000

5 Claims. (Cl. 74—81)

This invention relates to clothes washing machines and has for its object the provision of a new, simple, and economical mechanism whereby the vigor and amplitude of the washing action may be varied gradually all the way from zero to a maximum action of great intensity; the provision of an operating mechanism for washing machines which is very simple and inexpensive, and by which the violence of the washing operation can be varied as desired without stopping the machine; the provision of a washing machine mechanism wherein a variation of the stroke is employed in place of a clutch; while further objects and advantages of the invention will become apparent as the description proceeds.

In the drawings accompanying and forming a part of this application I have illustrated certain simple physical forms in which my inventive idea can be embodied, although it will be understood that these are intended to be merely illustrative of the principles of my invention which may also be embodied in a great many other specific physical forms.

Fig. 1 is a vertical sectional view corresponding to the line 1—1 of Fig. 2 showing part of a washing machine containing my improved mechanism; Fig. 2 is a bottom plan view of the machine shown in Fig. 1; Fig. 3 is a bottom plan view of another form of mechanism containing my improvements; Fig. 4 illustrates part of the mechanism shown in Fig. 3, other parts being removed; Fig. 5 is a vertical sectional view corresponding to the line 5—5 of Fig. 3; Figs. 6 and 7 are bottom plan views of still other mechanisms containing my improvements; Figs. 8 and 9 are detail sectional views taken on the lines 8—8 and 9—9 respectively of Fig. 7; Fig. 10 is a bottom plan view of yet another form of mechanism; Figs. 11 and 12 are sectional views corresponding to the lines 11—11 and 12—12 of Fig. 10.

The tub 1 may be of any suitable kind or shape and has a base-plate 2 to which the driving mechanism is attached. Carried centrally by this plate is a vertical bearing sleeve 3 in which is journaled a vertical shaft 40 which projects through the tub bottom, being provided at its lower end with a pinion 4 and at its upper end, inside the tub, with an agitator or dasher 5 of any suitable type.

Journalized on a vertical stud 6 carried by a bracket 7 at one side of the sleeve 3 is a gear wheel 8 meshing with a worm 9 carried by the horizontal shaft 10 of an electric motor 11. Also pivoted on a vertical axis to a second bracket 12 at a distance from the bracket 7 is a rocker 13 to which is secured one end of a horizontal rod

14. Sleeved slidably upon this rod is a yoke 15, said yoke being also pivoted to a stud 16 carried by the gear 8 eccentrically thereof. As the gear 8 is rotated, the rod 14 will be swung back and forth relative to the bracket 12 after the manner of a pendulum.

Slidably mounted on the rod 14 is a collar 17 to which is articulated one end of a toothed rack 18 meshing with the gear 4 and held in proper operative relation therewith in any suitable way as by the rocking stirrup 19. The rocker 13 is preferably offset sufficiently so that the collar 17 can be moved into line with the pivot axis at which time there is, of course, no reciprocation of the rack 18 and the washing action is wholly arrested. Suitable means are also provided such as the rod 20 pivoted to the collar 17 and fastened to the control lever 21 for sliding this collar along the rod 14 to vary the stroke of the rack between zero and a set maximum, any suitable sector 22 being provided for fixing the position of the lever.

In Figs. 3 to 5, the pinion 4 meshes with an arcuate rack 24 pivoted to the bottom plate at 25, the radius arm of this rack being provided with a stud 26 journaled in a rectangular block 27 which is slidably received in the arcuate slot 28 formed in the curved lever 29. One end of this lever is articulated to a connecting rod 30 pivoted on the eccentric stud 31 of the worm gear 8; the other end of said lever is articulated to a second lever 32 which is journaled to the same stud 7 which carries the worm gear 8. An adjusting rod 20 is connected to the same end of the lever 29 as is the arm 32, and leads to an adjusting lever 21, enabling the lever 29 to be moved as shown by full and dotted lines in Fig. 4. The slot 28 is carried beneath the pivot of the arm 32 (see Fig. 5) in such a way as to enable the stud 26 to be brought into line with this pivot, at which time there is, of course, no motion transmitted to the rack. Movement of the rack in the direction shown by the dotted lines in Fig. 4 increases the action as desired.

In Fig. 6 I have shown another modification wherein the stud 6, wheel 8, worm 9, shaft 10 and motor 11 appear as before, as also does the pinion 4 and rocker 13. In this embodiment, however, I have shown the rod 14 as directly articulated at one end to the stud 16 of the wheel 8, and having its opposite end slidably received in the box 33 of the rocker. Meshing with the pinion 4 is a segmental rack 34, carried by a rod 35 pivoted at 36 to the base plate.

Mounted on the rods 14 and 35 are the collars

17* and 37, respectively connected together by the link 38 which is pivoted to both the collars and also connected by the links 39, 39 to the hand lever 21. By pushing the two collars along their respective rods, the amount of stroke of the rack 34 can be varied from nothing at all, (when the collars are in line with the pivot of the rocker 13) to a very substantial amount when the collar 37 is nearest to the pivot 36.

10 In Fig. 7 I have illustrated yet another modification of my invention. In place of a rack and pinion I have shown the dasher shaft as provided with a pulley 4* around which is wrapped a flexible chain 41 having its ends fastened to a reciprocable bar 18* which is constrained to move in a fixed path by means of a suitable guide 23. Slidably mounted on a horizontal rod 42 carried by the bottom plate of the machine and perpendicular the bar 18* is a collar 43 having two laterally 15 extending arms 44 between whose extremities is pivoted the block 45 in which is slidably mounted the rocking lever 46. One end of this lever is slotted as shown at 47 for the reception of the stud 16 carried by the gear 8. While the opposite end of said lever is articulated to the bar 18*. This last articulation is preferably accomplished by means of two bifurcated yokes, one carried by the bar 18* and having arms 49, 49 pivoted at 50 to the arms 51, 51 of the other yoke which is carried by the lever 46. In this way a recess is defined into which the block 45 can be moved by the action of the control lever 21 and control rod 20. The action of this control rod is to change directly the ratio of the lever arms whereby the stroke of the rack is varied from nothing at all to a predetermined maximum.

In Figs. 10 to 12 the mechanism comprises the same pinion 4, but the worm gear 8 is here provided with an eccentric 55 connected by means of 40 a pitman 56 to one arm 57 of a bell crank lever whose other arm 58 is formed with a longitudinal slot 60. This bell crank lever is pivoted to a vertical stud 61 carried by a bracket 62 located at the intersection of the two arms 57 and 58. Meshing with the pinion 4 is an arcuate rack 63 formed at one end of a slotted arm 64 pivoted at 65 to another bracket 66 on the base plate. The bell crank lever 58 is arranged to swing just above the arm 64 and parallel to the plate of that arm. Slidably mounted in the slot 60 is a block 67 and slidably mounted in the slot of 64 is a second block 68 the two blocks being fastened rotatably together by means of a pivot pin 69 passing through a washer 70 interposed between the two levers; 55 and articulated to this pin is the adjusting rod 20 connected to the control lever 21.

The slot 60 runs past the pivot 61 as shown in Fig. 10 so that when the pivot pin 69 is brought into line with the pivot 61, no motion will be transmitted to the rack 63, although the bell crank lever oscillates through the same arc and at the same speed with all loads.

It is desirable in washing machines to vary the vigor of the washing action depending upon the nature of the articles being washed, the amount of liquid present and other conditions. This mechanism enables the intensity of the washing action to be gauged to the conditions required. It will be understood however, that a great many changes in detail can be made without departing from the scope of my inventive idea, and I do not limit myself in any wise except as specifically recited in my several claims which I desire may be construed broadly, each independently of limitations contained in other claims.

Having thus described my invention what I claim is:

1. In a device of the type described, the combination with an oscillatably driven member of variable stroke driving mechanism therefor comprising, a motor, a speed reducing worm and worm gear set driven by said motor, a fulcrum lever pivoted for oscillation about a vertical axis, means eccentrically connecting said lever to said worm gear, a pivot bearing for said lever mounted 10 for adjustable movement in a horizontal plane, a driving connection between said lever and said driven member comprising a member pivotally and slidably connected to said lever, and means including said pivot bearing for changing the position of the pivotal connection between said last named member and lever relatively to the axis of said lever during the operation of said mechanism for varying the amplitude of stroke of said driven member. 20

2. In a device of the type described, the combination with an oscillatably driven member of variable stroke driving mechanism therefor comprising, a motor, a speed reducing worm and worm gear set driven by said motor, a fulcrum lever 25 pivoted for oscillation about a vertical axis, means eccentrically connecting said lever to said worm gear, a driving connection between said lever and said driven member comprising a member pivotally and slidably connected to said lever, and means including an element pivoted at one end for movement about a vertical axis and pivotally connected at its other end to said lever for moving the position of the pivotal connection between said last named member and lever during the 30 operation of said mechanism for varying the amplitude of stroke of said driven member.

3. In a device of the type described, the combination with an oscillatably driven member of 40 variable stroke driving mechanism therefor comprising, a motor, a speed reducing worm and worm gear set driven by said motor, a fulcrum lever pivoted for oscillation about a vertical axis, a pitman eccentrically and pivotally connected at one end to said worm gear and at its other end to said 45 lever, a driving connection between said lever and said driven member comprising a member pivotally and slidably connected to said lever, and means including an element mounted for adjustable movement about said worm gear providing a pivot bearing for said lever for moving the position of the pivotal connection between said last named member and lever during the 50 operation of said mechanism for varying the amplitude of stroke of said driven member. 55

4. In a device of the type described, the combination with an oscillatably driven member of variable stroke driving mechanism therefor comprising, a motor, a speed reducing worm and worm gear set driven by said motor, a fulcrum 60 lever pivoted for oscillation about a vertical axis, a pitman eccentrically and pivotally connected at one end to said worm gear and at its other end to said lever, a gear pinion fixed on said driven member, a back-and-forth moving toothed member meshing with said pinion, pivotal and slideable connections between said toothed member and said lever, and means including an oscillatably adjustable link providing a pivot bearing at its free end for said lever for moving the position of the pivotal connection between said toothed member and lever during the operation of said mechanism for varying the amplitude of stroke of said driven member. 70

5. In a device of the type described, the com- 75

bination with an oscillatably driven member of variable stroke driving mechanism therefor comprising, a motor, a speed reducing worm and worm gear set driven by said motor, a fulcrum lever 5 pivoted for oscillation about a vertical axis, a pitman eccentrically and pivotally connected at one end to said worm gear and at its other end to said lever, a gear pinion fixed on said driven member, a toothed member mounted for oscillation about a fixed axis and meshing with said pinion, pivotal connections between said toothed

member and said lever, said connections being slidable with respect to both said toothed member and lever, and means including a link pivoted at one end for movement about the axis of said worm gear and providing at its other end a pivot bearing for said lever for moving the position of the pivotal connection between said toothed member and lever during the operation of said mechanism for varying the amplitude of stroke of said driven member. 5
